(**) Term: **14 Years**

(57) **CLAIM**

(21) Appl. No.: **29/139,312**

The ornamental design for an access point for wireless LAN systems, as shown and described.

(22) Filed: **Mar. 28, 2001**

DESCRIPTION

(30) **Foreign Application Priority Data**

Feb. 26, 2001 (KR) 01-4422

FIG. 1 is a perspective view of the access point for wireless LAN systems;

(51) LOC (7) Cl. **14-02**

FIG. 2 is a front view thereof;

(52) U.S. Cl. **D14/439**; D13/162

FIG. 3 is a rear view thereof;

(58) Field of Search D14/432, 433,

FIG. 4 is a left side view thereof;

D14/434, 218, 439; D13/158, 162, 164,

FIG. 5 is a top plan view thereof;

184, 182, 159, 160; D10/106; D21/324;

FIG. 6 is a bottom view thereof; and,

340/825.22, 825.24, 825.25; 455/151.2,

FIG. 7 is a perspective view thereof showing the article used
151.3, 151.4, 352-355 with rotatable antennas mounted thereon, the broken lines of
antennas are for illustrative purposes only and form no part
of the claimed design.
